BALTHAZARD AND ARTHUR KOWASKI, OF MILWAUKEE, WISCONSIN

RAILROAD CROSSING GATE

Application filed October 17, 1929. Serial No. 400,315.

This invention relates to railroad crossing gates, and more particularly to a car actuated circuit closer for bringing about the automatic operation of the gates.

5 One of the objects of my invention is the provision of a railroad crossing gate, wherein the usual gate members are automatically lowered by an approaching train, and after the train has passed beyond the crossing, the 10 gates are automatically raised through suitable operating mechanism controlled by novel car actuated circuit closers forming the subject matter of this invention.

It is a well known fact that it is of considerable expense to maintain an operator at each railroad crossing for operating the closure gates for closing the crossing against pedestrians and vehicle travel, and, therefore, it is one of the main objects of my invention to 20 provide means whereby the closure gates can be automatically operated by the train actuating my novel circuit closers, which control suitable mechanism for raising and lowering the gates.

25 A further and more specific object of my invention is the provision of novel train actuated circuit closers, which will be durable and efficient in use, one that will be simple and easy to manufacture, and one which can be 30 placed upon the market at a reasonable cost.

With the above and other objects in view, the invention consists in the novel features of construction, the combination and arrangement of parts hereinafter more fully set forth, pointed out in the claims and shown in the accompanying drawings wherein:

Figure 1 is a side elevation, with parts thereof broken away and illustrated in cross section, of one of the switch members with a contact arm to be engaged by the train;

Figure 2 is a view similar to Figure 1, illustrating the switch member and contact arm adapted to be engaged by the train upon approaching the crossing; and,

45 Figure 3 is a diagrammatic view of the electric connection.

Referring more particularly to the drawings, wherein various reference characters are used to designate the several parts throughout the views, it will be noted that in order

to operate the gates for lowering the same upon the approach of a train, I arrange at a suitable distance from the highway crossing, switch housings 3 and extending transversely through each housing is a shaft 4 upon which 55 is mounted counter balance weight 5, and a cam member 6 formed with an offset shoulder 7. Upon the exterior of the housing 3 and connected to the shaft 4 is an arm 8 which projects upwardly in the path of an approaching train and when engaged by the train is moved downwardly to the left as shown in Figure 2, rotating the shaft 4 and simultaneously rotating the weight 5 and cam 6. The movement of the arm 8 downwardly 60 will be sufficient to allow the shoulder 7 to pass the reciprocating rod 9 carried by the solenoid 10, and as the rod 9 moves upwardly it carries with it a pivoted arm 11 which has a contact 12 at its outer end to engage a contact 13 and completing a circuit to a second solenoid 14, the purpose of which will be 65 hereinafter more fully set forth.

As noted in Figure 2, the arm 11 is pivotally mounted upon a suitable bracket 15 at one 70 side of the housing 3 and this arm has a slot 16 formed in its intermediate portion to receive a pin 17 on the rod 9 whereby to permit free movement of the arm 11 upon its pivot.

It will be further noted from Figure 2, the 75 arm 8 is so constructed that it will move in one direction, to the right, without rotating the shaft 4 and in order to maintain the arm 8 in a normal upright position for engagement by a train approaching a crossing, a 80 curved arm 18 projects outwardly from one side thereof and is yieldably connected by means of a coil spring 19 to an ear 20 on the hub of the arm which is fixed to the shaft whereby a train engaging the arm 8 after 85 leaving the crossing, or should the arm be engaged by a train switching or moving against the arm in one direction, the arm can be moved to the right without moving the shaft 4, thus placing spring 19 under tension which 90 will assist the arm 8 to its normal operative position after the train has passed there-over.

When a train approaching a crossing engages arm 8 and brings the contacts 12 and 100

13 into engagement, a circuit to solenoid 14 is completed. This solenoid forms a part of the gate control mechanism, which will not be described or illustrated in this application, 5 as the same forms a subject matter of another invention.

Referring to the diagrammatic view shown in Figure 3, it will be noted that when contact point 12 engages contact points 13, it closes the circuit to the motor 44, thus starting the motor in operation, which motor also forms a part of the gate operating mechanism (not shown).

After the train has moved a sufficient distance beyond the highway crossing, it engages an upwardly projecting arm 89, connected to a rotative shaft 90, extending transversely of housing 91. Shaft 90 carries a contact finger 92 adapted to be moved into engagement with the contact 93 for closing a circuit through the medium of switch member 94 and contacts 95 and 95', to solenoids 10 and 43, the solenoid 43 forming a part of the railroad gate raising mechanism (not shown).

25 Carried by shaft 90 is a counter balance weight 96 which is adapted to be moved into position for returning arm 89 to its upright position after the train has passed beyond housing 91 so that this arm 89 will always be
30 in position to be engaged by a train passing the housing.

It will be noted that upon release of the solenoid 10, the core rod 9 which has been urged upwardly by a coil spring 97 will be returned to its normal operative position shown in Figure 2, disengaging the outer end of the rod 9 from the shoulder 7 whereby the counter balance member 5 will return arm 8 to its normal upright position.

40. From the foregoing description, it can be seen that I have provided an exceptionally simple and durable form of circuit closers, which can be readily actuated by a passing train.

45 While I have shown and described the preferred embodiment of my invention, it will be apparent that slight changes may be made in the construction when putting the invention practice without departing from the 50 spirit of the same or the scope of the appended claims.

I claim:

1. In a car actuated circuit closer, a housing, a transverse shaft therein, a cam on the shaft having a shoulder portion, a solenoid having the outer end of its core bearing on the cam, a pivoted lever carried by the housing and operatively connected with the core, an arm projecting vertically from the housing and adapted to be engaged by an object passing thereover for rotating the shaft causing rotation of the cam whereby the core of the solenoid will pass the shoulder portion imparting movement to the lever, a contact carried by the lever, and a stationary contact

adapted to be engaged by the contact on the lever for completing a circuit.

2. In a car actuated circuit closer, a housing, a transverse shaft therein, a cam on the shaft having a shoulder portion, a solenoid having the outer end of its core bearing on the cam, a pivoted lever carried by the housing having a longitudinal slot intermediate its ends, a pin carried by the core and engaged within said slot to connect the lever and core, an arm carried by the shaft and projecting vertically from the housing and adapted to be engaged by an object passing thereover for rotating the shaft causing rotation of the cam whereby the core of the solenoid will pass the shoulder portion for imparting movement to the lever, a contact carried by the lever and a stationary contact carried by the housing and adapted to be engaged by the contact on the lever for completing a circuit.

In testimony that I claim the foregoing I have hereunto set my hand at Milwaukee, in the county of Milwaukee and State of Wisconsin.

CONRAD STRACKBEIN.
